UNITED STATES PATENT OFFICE.

FRANK S. BALDWIN, OF ST. LOUIS, MISSOURI.

PERMUTATION-LOCK.

SPECIFICATION forming part of Letters Patent No. 254,450, dated March 7, 1882.

Application filed November 9, 1881. (Model.)

To all whom it may concern:

Be it known that I, FRANK S. BALDWIN, of St. Louis, Missouri, have made a new and useful Improvement in Permutation-Locks, of which the following is a full, clear, and exact description, reference being had to the annexed drawings, making part of this specification, in which—

Figure 1 is a view in perspective of the improved lock; Fig. 2, a view in perspective of one set of the movable parts of the lock, the parts being shown detached from each other; Fig. 3, a vertical section taken through a drawer having the lock; Fig. 4, a view in perspective of one of the stops; Fig. 5, a section taken through one of the inner disks, and Fig. 6 a section taken through one of the outer disks.

The same letters denote the same parts. The present invention is an improvement in that class of permutation-locks wherein a series of duplicate knobs, dials, and disks is employed, the various members of the series, while acting in combination, being separated from each other.

It relates partly to the means used in preventing the position of the inner disks from being determined by one endeavoring to pick the lock; partly to the means for aligning the disks, and partly to the means for preventing the disks from being detached from the spindle by friction produced by pulling the knob outward, so as to cause the disks to bear flatwise against the plate or other part of the construction, and sufficiently, unless prevented as described, to cause the disks to become loosened and detached from the spindle.

Referring to the drawings, A represents a lock of the class referred to, and having the improvement under consideration, having the plate B, the tubes C C C, the knobs D D D, the dials E E E, the spindles F F F, the disks, G G G, the disks H H H, the screws I I I, and the stops J J J. The tubes C, as well as the tubes for holding the stops J, are attached permanently to the plate B, projecting toward the outer side of the drawer or door to which the lock is attached. The spindles F are inserted in the tubes C, passing from the outer end thereof just through the plate B, and coming even with the inner end of the tube. The

spindles, at their inner ends, are perforated longitudinally to receive the screws I. They are also notched at f. The screws I are used to fasten the disks G and H to the spindles, 55 the disks G being next to the spindles, and the disks H next to the disks G. The disks G, in addition to the slots g g, which are arranged radially in the disks, have the projections g', and the disks H have the slots h and 60 the projections h', which last-named parts project toward the disks G, and are made to fit into the slots g, and when the parts are in place the projections g' engage in the notches f of the spindles. 65

The plate B constitutes the frame of the lock, having the flange b, and being slotted at b' b' b' to receive the catches K.

The dials E have the usual numerals, as shown, and they may have projections e upon 70 their faces. Each dial is in one piece with the knob and spindle, and when the screw I is screwed up the knob, dial, spindle, and disks turn as one piece, and as they turn the slots g g come successively opposite the stop J. The 75 latter is pressed toward the disks by means of the spring j, causing the stop to enter the slots g as they are successively presented. The head j' of the stop, however, is rounded or beveled, 80 enabling the knob and dial to be rotated by the operator, the stop retreating into the tube j' as each space between two consecutive notches is presented. The movements of the stop produce a clicking sound, indicating the number of slots passing the stop, and thus locating, 85 when the relative position of the stop to the other parts of the lock is known, the position of the notch h. The chief aim of the stop, however, and for this purpose it presses with sufficient force into the notches g, is to insure the 90 proper alignment of the disks G and H with reference to the slot b' in the plate B, and so as to cause the slots g and h to come successively exactly opposite the slot b'. Each one of the slots g in the disk G coincides in size 95 with the slot h of the disk H, and when the disks G and H are placed against each other one of the slots g coincides with the slot h, as seen in Fig. 1, and when the disks G H are turned so as to bring the slot h opposite the slot b' the drawer or door can be opened, the catch K passing through the slot. Now, the

series of slots *g* in the disk G provide, as hereinafter explained, for the changing of the combination of the lock. They, however, are especially valuable in this: When the two disks 5 G H are together in position the notches *g*—saving that notch for the time being opposite and in coincidence with the notch *h*—constitute a series of what may be termed "false" notches, into which the catch K falls when the 10 drawer or door is drawn out by a person aiming to pick the lock, for it is customary on the part of those attempting to pick locks of the present kind to draw the locking-disk H against the catch, and then turn the disk around until 15 the slot therein is opposite the catch, whereupon the catch enters the slot, indicating the position of that disk for opening the lock, and then having located the proper position of one disk proceed similarly in locating the positions 20 of the remaining disks. This procedure is interfered with in the present case, the catch entering the false notches as fast as they are presented, serving to constantly mislead the operator, who cannot tell whether the catch has entered the single true opening or one of the many 25 false openings. So far as this especial feature of the improvement is concerned the disks G and H might be a single piece, having one opening—such as *h*—extending entirely through the 30 o disk, and a series of indentations of shape and size suitable for allowing the catch to enter therein; but by making the disks G and H separate pieces the combination of the lock can be changed, which is done by loosening the screw 35 5 sufficiently to enable the projection *h'* of the disk H to be withdrawn from the notch *g* of the disk G and then turning the disk H (relatively to the disk G) around as desired, then inserting the projection *h'* in another of the 40 notches *g*, and then tightening the screw I, as before.

The disk G, by reason of the projections *g'* entering the notches *f* of the spindle, preserves a constant relation to the dial. These projections *g'* and mode of uniting the disks G H and 45 spindle also serve to prevent the various parts of the lock from being detached from each other by drawing the disks hard against the plate B and then turning the knob around with a view to unscrewing the screw I, which might 50 occur if the disk could be turned upon the spindle. The projections *g'* prevent this, the disks and screw turning with the spindle.

In the present illustration three sets of knobs, 55 dials, spindles, disks, and stops are used in combination, enabling one thousand combinations to be employed. The series, however, may consist of any desired number.

The lock is operated in the customary manner, turning the various knobs and dials to suit 60 the combination for the time being used. The lock can also be operated in the dark, in which case the projections *e* upon the dials are brought into use, and the desired positions of the disks obtained by touching the projections *e* and 65 listening to and counting the clickings of the stops J.

I claim—

1. A permutation-lock having, in combination, the spindle F, having the notches *f*, the 70 disks G, having the projections *g'*, and the slots *g*, the disk H, having the projection *h'*, and the screw I, substantially as described.
2. The combination of the disk G, having the notches *g*, the disk H, having the slot *h*, 75 the spindle F, the plate B, and the stop J, substantially as described.

FRANK S. BALDWIN.
